UNITED STATES PATENT OFFICE.

JOSEPH ARTHUR PARKER, OF CWMBRAN, WALES.

APPARATUS FOR THE ELECTRODEPOSITION OF METALS ON WIRE OR NARROW STRIP.

Application filed March 19, 1926, Serial No. 95,961, and in Great Britain May 23, 1925.

This invention relates to a process and apparatus for the electro-deposition of metals on wire and narrow strip, hereinafter termed wire.

5 A coiled bundle of wire is well known in commerce and will be hereinafter referred to as a bundle, the wire being wound into a bundle as it leaves the draw plate.

According to the invention an unplated 10 bundle of wire, while still coiled and with its convolutions spread apart is passed through the solution contained in a plating tank from the one end of said tank to the other and the bundle, while being so passed 15 through the tank, is slowly revolved substantially about its own axis, the convolutions being gathered in after plating and the plated bundle is collected beyond the other end of the tank. The process therefore starts with an unplated bundle of wire 20 and finishes with a plated bundle of wire, without any uncoiling of the wire.

Although the convolutions of the bundle are axially opened out while being passed 25 through the plating tank, the wire treated is in continuously coiled condition; and, when one bundle has been passed through the tank, one end of a further bundle can be connected up to the trailing end of the 30 first bundle so as to make the two bundles a continuous coiled length, in order that the process of plating can continue in respect to bundle after bundle.

The opened out convolutions, as they 35 travel through the plating solution, pass closely between anode surfaces provided in the tank, so that there is little electrical resistance.

Further, while the convolutions are being 40 so passed through the tank they may, in addition to being revolved, be agitated, oscillated or rocked.

The apparatus comprises a horizontally 45 disposed revoluble main shaft adapted to have a bundle of wire hung thereon and along which the opened out convolutions are caused to pass by the revolution of the shaft. This shaft is arranged over the plating tank, and from it hang the bundles and 50 the separated convolutions, as well as the bundles outside the tank and the convolutions being treated within the tank. The revolution of the shaft may alone be depended upon for causing the opened out 55 convolutions to pass through the plating tank.

Each opened out convolution of wire makes a considerable number of revolutions in the plating tank according to the length of the plating tank and the pitch of the convolutions, so that, by the time each convolution leaves the tank, it is sufficiently plated for requirements. 60

An electro-deposition unit preferably comprises a tank containing hydrochloric acid 65 or other cleaning liquid, a swill tank containing water, a sulphuric acid tank, a plating tank, a washing tank, and a drying tank, all arranged in succession below the revoluble main shaft, and the opened out 70 convolutions of the bundle pass through these tanks in order.

The apparatus according to the invention also contemplates a certain arrangement of anodes in the plating tank, and utilizes the 75 main shaft as a cathode connection.

The invention will be hereinafter more particularly described with reference to the accompanying drawings, in which:

Fig. 1 is a longitudinal section of an electroplating unit embodying the invention. 80

Fig. 2 is a plan view of the apparatus shown in Fig. 1.

Fig. 3 is a transverse section on the line A—B, Fig. 1. 85

Figs. 4 and 5 are detail sectional views, on a larger scale, showing how the anodes are applied to the interior of the plating tank.

Fig. 6 is a diagrammatic view showing 90 how the convolutions are agitated or rocked in addition to being revolved.

A number of tanks *a*, *c*, *d*, *e*, *f* and *g* are provided in succession for treatment of the wire. The tank *a* contains hydrochloric acid 95 or other cleaning liquid, the tank *c* swill water, the tank *d* sulphuric acid, the tank *e* electroplating solution, and the tank *f* washing liquid, while *g* is a drying tank.

It will be understood that a plating tank 100 only may be used.

h is a revoluble main shaft arranged above the tanks and having its ends extending beyond the ends of the outer tanks and having at one end a spool *i* upon which a bundle of wire to be treated may be hung and at its other end with a spool *j* upon which the treated convolutions of wire are collected. This shaft may be revolved from the pulley *y*. 105

An unplated bundle of wire is hung upon the spool *i* between the end plates *i*² and *i*³. 110

and one of its ends is manually threaded through the machine with the convolutions spread apart, so that said convolutions successively pass into and out of the respective tanks while hanging from the shaft h , one or two of said convolutions being ultimately started to wind up into a bundle on the outgoing spool j . This movement or passage of the wire through the tanks is clearly indicated by dotted lines in Fig. 2.

That part of the shaft h which extends above the plating tank is formed with spaced flanges h^3 forming grooves h^2 to guide the convolutions and keep them apart, since in this tank they must be kept separate and clear of the anodes, which are arranged within the tank as hereinafter described. The shaft h forms the cathode connection to the plating tank.

It will therefore be clear that the convolutions pass through all such tanks in succession and are plated during the passage, and that the process starts with an unplated coiled bundle of wire on the in-going spool i and finishes with a plated coiled bundle on the outgoing spool j , there being no uncoiling of the wire in its passage through the apparatus.

The revolution of the shaft h is depended upon to revolve the wire convolutions about their own axes, and also to feed the wire convolutions through the tanks.

That part of the shaft which lies above the plating tank e , and which is provided with the grooves h^2 , has electrical brushes k which bear against the flanges h^3 which form the grooves, for the purpose of leading the current away from the plating tank, these brushes being suitably mounted upon a frame l supported above the tank on the fixed bearers l^2 and l^3 , from which also hang the bearings h^4 and h^5 which support the shaft h .

Since the revolution of the shaft h is depended upon to revolve the convolutions and bundles, its diameter is desirably large in order to increase frictional contact with the wire, and, as shown, at h^6 and h^7 , said shaft is built up of tubular pieces, the interior one, h^8 , being of metal, the outer one, h^9 being formed of a sleeve of india-rubber, and that part of the shaft which extends over the plating tank and formed with the grooves h^2 being formed of electrical conducting material.

The electro plating tank e may be provided with any convenient form of anodes, but preferably, and as shown in the drawings, same are in the form of plates extending transversely across the tank from side to side of the latter, so that each convolution of wire passes between two transverse stretches of anode plates.

m (Fig. 3) represents a transverse stretch of anode plates built up of four separate

plates, m^2 , m^3 , m^4 , and m^5 , having their opposite vertical edges seated in grooves n in the sides of the tank and in grooves o in a central support p fixed within the tank below the shaft h . The lower anode plates, m^4 and m^5 , rest upon bearers q at the bottom of the tank, and these plates are separated from the upper plates m^2 and m^3 , by non-conductive glass or other insulating sleeves r , which are of a diameter greater than the thickness of the plates and are threaded upon rods r^2 . Lead or other conducting blocks r^3 also fitting within the grooves n and o , are connected to the opposite ends of the rods r^2 whereby the upper and lower anode plates are electrically connected to each other. The upper edges of the upper pair of plates m^2 , m^3 , are also provided with glass or non-conductive sleeves s . Similar vertical glass sleeves or rods t extend vertically from the central bearer q between the inner ends of the lower anode plates m^4 and m^5 . The sleeve t is supported by one of the bearers q and by the central support p , the object being that each convolution of wire, indicated at x in Fig. 3, shall be guided between each stretch of anode plates m by the glass tubes or rods r , s , and t so that no part of the wire shall touch the surface of any of the anode plates, it being understood that in the plating tank e there are numerous transverse stretches m of anode plates close together and fed with current by the leads u from positive current carrying bars u^2 and u^3 .

Figs. 4 and 5 show clearly how the end of the anode plates extend into the grooves in the sides of the tank, and also how the glass sleeves r extend between the upper and lower anode plates. Each of the upper glass tubes s is applied to a rod supported at one of its ends by a clip s^2 carried by the upper edge of one of the anode plates and by engagement of its other end in the groove in the support p .

At the in-going end of the apparatus a device v serves to hammer out any kinks or bends in the wire convolutions as they leave the in-going spool i and before they reach the tanks. This device comprises a bell cranked lever v^2 , a stationary anvil v^3 , teeth v^4 formed on the side plate i^2 of the spool i , and a lever v^5 hanging from the support l^2 . As the shaft h revolves, the teeth v^4 will rock one arm of the bell cranked lever v^2 and cause the other arm of the said lever to give a swinging blow to the lever v^5 against the anvil v^3 , between which anvil v^3 and lever v^5 the convolutions are guided, but this device is not a material part of the invention.

In Fig. 6 the shaft h is shown as carrying a toothed wheel 2 gearing with two toothed wheels 3 and 4 on stub spindles 5 and 6 carrying short radial arms 7 and 8. These stub

spindles are supported upon a frame 9 from a supporting bar 10, and as the shaft *h* revolves it causes the radial arms 7 and 8 to give intermittent blows to the convolutions of wire *x* on both sides of the shaft *h*, so that the convolutions, in addition to revolving, are agitated or rocked on the shaft as fulcras.

If the bundle to be treated is so deformed that its convolutions would pay off untruly a device of any suitable construction may be placed in front of the in-going tank to true up said convolutions.

Having now described my invention what I claim and desire to secure by Letters Patent is:—

1. Apparatus for electro-plating a coiled bundle of wire comprising a tank to contain plating solution, means for passing the opened out convolutions of a bundle of wire through the tank from one end to the other and revolving the bundle of wire substantially about its own axis, plate anodes extending transversely of the plating tank and spaced apart and between which each convolution of wire passes in its travel through said tank, means for preventing the convolutions of wire touching the anode plates, anode connections to said plates and cathode connections to the wire to be treated, substantially as described.

2. Apparatus for electro-plating a coiled bundle of wire comprising a tank to contain plating solution, means for passing the opened out convolutions of the bundle through the tank from one end to the other and revolving the entire bundle substantially about its own axis, a series of spaced anode plates extending transversely of the plating tank and between which each convolution passes, each of said plates comprising a plurality of members electrically connected and arranged edgewise with their adjacent edges separated, means associated with each anode plate for preventing the convolutions of wire touching the anode plates and suitable electrical connections to said anode plates and to said wire, substantially as described.

3. Apparatus for electro-plating a coiled bundle of wire comprising a tank to contain plating solution, a revoluble shaft arranged over the tank to extend through and support the convolutions of a bundle of wire and revolve said convolutions about the axis of the bundle, said shaft having means for feeding said convolutions through the tank, means for spreading the convolutions of the wire, a support extending from one end to the other, and longitudinally of the tank below the shaft, a succession of spaced series of anode plates disposed transversely of the tank and between which each convolution passes, the plates of each series being supported be-

tween the longitudinal sides of the tank and 65 the central support so as to be removable from the tank for renewal, means for preventing the convolutions of wire touching the anode plates and electrical connections to the anode plates and to the shaft, substantially as described.

4. Apparatus for electro-plating a coiled bundle of wire comprising a tank to contain plating solution, means for passing the opened out convolutions of the bundle 75 through the solution of the tank from one end to the other and revolving the entire bundle substantially about its own axis, plate anodes spaced apart and extending transversely of the tank and between which 80 each convolution passes, means for preventing the convolutions of wire touching the anode plates, means for agitating the convolutions within the tank, and electrical connections to the anode plates and to the bundle of wire, substantially as described.

5. Apparatus for electro-plating a coiled bundle of wire comprising a tank to contain plating solution, a revoluble shaft arranged over the tank to extend through and support the convolutions of a bundle of wire, means for opening out the convolutions of the bundle, means associated with said shaft for feeding the convolutions through the tank from the one end to the other, means 90 for agitating the convolutions within the solution from the shaft as a fulcrum, a support extending longitudinally of the tank below the shaft, a succession of spaced series of anode plates extending transversely 100 of the tank and between which each convolution passes in its movement through the tank, the plates of each series being removably supported between the longitudinal sides of the tank and said longitudinal support, means for preventing the convolutions of wire touching the anode plates and electrical connections to the anode plates and to the shaft, substantially as described.

6. Apparatus for electro-plating a coiled 110 bundle of wire comprising a plurality of tanks to contain different solutions, means for passing the opened out convolutions of a bundle of wire through said tanks from one end to the other of said tanks, means for 115 revolving said bundle substantially about its own axis, plate anodes spaced apart and extending transversely of one of said tanks so that each convolution passes successively between adjacent plate anodes, means for preventing the convolutions of wire touching the anode plates and suitable electrical connections to said anode plates and to the bundle of wire, substantially as described.

In testimony whereof I have hereunto set 125 my hand.

JOSEPH ARTHUR PARKER.
